UNITED STATES PATENT OFFICE.

ROBERT H. IRVING, OF GRAMERCY, LOUISIANA.

FUEL-REGULATING SYSTEM.

1,407,422.

Specification of Letters Patent. Patented Feb. 21, 1922.

Application filed October 8, 1920. Serial No. 415,624.

To all whom it may concern:

Be it known that I, ROBERT H. IRVING, a citizen of the United States, residing at Gramercy, in the parish of St. James and State of Louisiana, have invented certain new and useful Improvements in Fuel-Regulating Systems, of which the following is a specification.

This invention has for its object the provision of a simple and efficient apparatus whereby the draft through a steam boiler furnace will be automatically controlled and at all times be determined by and in proportion to the steam pressure. The invention is designed particularly for use in connection with furnaces burning liquid or gaseous fuel and provides means whereby the supply of the fluid fuel and the steam for atomizing the same will be automatically regulated accordingly as the steam pressure rises or falls. The invention is illustrated in the accompanying drawings and will be herein-after fully set forth.

In the drawings—

Figure 1 is a conventional elevation of an apparatus embodying my present improvements;

Fig. 2 is a detail sectional elevation of the valve for controlling the flow of the steam or of the fuel to the burners;

Fig. 3 is a detail section through the valve employed to regulate the flow of fuel immediately adjacent the burner and also to control the flow of steam to the pump when the pump is working at its maximum capacity.

Fig. 4 is a detail end elevation showing the manner in which the fuel supply pipe is connected with the pump.

In the drawings, the reference numeral 1 indicates a furnace which is constructed to burn fluid fuel and which may be one of a gang of furnaces as will be readily understood. 2 designates the trunk steam line leading from the steam dome of the furnace to the several points of use and 3 indicates a smoke flue rising from the furnace and communicating with a trunk smoke conduit 4. Within the flue 3, I provide a damper 5 which may conveniently be a sheet metal plate approximately equal in length to the width of the said flue and provided at its ends with trunnions journaled in the sides of the flue. One of the trunnions is equipped with extensions carrying a counterweight 6 and a chain 7, the

latter depending from the extension to a point where it may be readily grasped by the attendant. The damper 5 is to be set in accordance with tests made upon the particular furnace to which it is applied so that the active opening through the flue 3 will be proportionate to the maximum draft required for the successful operation of the furnace. Within the smoke conduit 4, I mount a damper 8 which may also be a sheet metal plate of proper dimensions provided at its ends with trunnions journaled in the sides of the conduit. As shown clearly in Fig. 1, one of the trunnions has secured thereto a crank or lever arm 9 upon which is suspended a counterweight 10 and to which is attached a chain 11 rising from the arm and passing around guide pulleys 12 to a coupling head 13. From the coupling head 13, a chain 14 is extended to a damper regulator 15 which is illustrated conventionally inasmuch as the details of its construction constitute no part of my present invention and it may be of any well-known type, a pipe 16 connecting the said damper regulator with the trunk steam line 2, as shown. When the steam pressure has been raised to the desired point the damper regulator 15 is so set that the damper 8 will be closed, which is the position illustrated in Fig. 1, and as the steam pressure falls the coupling head 13 is permitted to descend and pull upon the chain 11 in opposition to the counterweight 10 so that the damper will be opened. This operation is the same as that of various types of damper regulators now on the market and will be readily understood by those skilled in the art. In carrying out my invention, I provide an indicator board 16' at any convenient point within the furnace room and mounted to play over the said board is an indicator arm 17 which is fulcrumed in any convenient manner intermediate its ends and has one end attached to the chain 14, as shown, so that its free end will play over the board and by its position relative thereto will denote the position of the damper.

A branch 18 leads from the steam trunk line 2 and supplies the steam through a second branch 19 to the burner-feeding pipes 20 which lead into the burners 21 and are provided with cut-off valves 22 near the burners, as shown. The burners are illustrated in the present drawings in a conventional manner only, but it may be

stated that they are of a type invented by me whereby the steam for atomizing the fuel is cut-off after the flow of fuel has been cut-off and the flow of the steam is set up automatically before the flow of fuel is permitted in order to avoid an accumulation of fuel in the combustion chamber of the fire box and, consequently, prevent explosions. The fuel generally used by me is crude oil and it is drawn from a storage tank or other source of supply by a pump 23 and forced through the oil line 24 and the branches 25 thereof to the burners, as will be readily understood. The branches 25 are equipped with cut-off valves 26 adjacent the burners and between the said cut-off valves and the burners I provide firing valves, indicated at 27. One of the firing valves is illustrated in detail in Fig. 3 and, as shown in said figure, comprises a casing 28 provided with nipples 29 and 30 for connection with the adjacent portions of the branch 25, the nipple 29 being the inlet nipple. The casing 28 is constructed with a tapered bore disposed at a right angle to the passage provided through the nipples 29 and 30 and at diametrically opposite points of the said bore and in axial alignment with the bores of the nipples 29 and 30 I provide the inlet port 31 and the outlet port 32. The inlet port 31 is preferably circular of such a diameter as to accommodate the maximum fuel requirements, while the outlet port 32 is enlarged and expanded laterally so that it presents an elliptical passage for the fuel. Within the casing 28 is mounted a turning plug 33 which is tapered throughout the greater portion of its length so as to fit snugly within the casing and this plug is provided with a port 34 therethrough which at its entrance end is of the same form and dimensions as the port 31 while at its outlet end it corresponds to the outlet port 32 in form and dimensions thus constituting a venturi passage for the fuel. The construction thus set forth in detail permits a ready flow of the fuel while at the same time it causes the pressure of the fuel to be increased at the point where it enters the valve so that any impurities which may happen to be in the fuel will be carried through the valve and choking of the valve will, consequently, be prevented. The construction also permits an expansion of the fuel as it passes through the outlet and thereby facilitates its subsequent atomization at the burner. One end of the plug is extended beyond the end of the casing through a suitable packing gland, indicated at 35, and is equipped with an operating handle 36 so that it may be turned to bring the port or venturi passage 34 into proper relation to the ports 31 and 32 and thereby regulate the flow of the fuel. After the plug

has been thus set, a set screw 37 mounted in the cap 38 is turned home against the butt end of the plug so as to hold it in the set position and thereby prevent accidental disarrangement of the valve. 70

Within the steam pipe 19, I provide a regulating valve 39 which may be generally described as a check valve having its stem 40 projecting through the upper side of the valve casing. Upon the upper side of the valve casing, I secure a bracket or supporting plate 41 and upon one end of said plate I erect a post 42 upon the upper end of which is pivoted one end of a lever 43. The stem 40 carries a yoke 44 through which the said lever passes and mounted within the yoke above and below the lever are pulleys 45 which serve to maintain the lever in proper relation to the yoke and at the same time accommodate the relative movement of the lever and the yoke without causing excessive wear upon the edges of the lever. The yoke is also preferably pivoted to the upper end of the stem 40, as indicated at 46, so that it may follow the pivotal movement of the lever to some extent and thereby avoid binding and bending of the valve stem. The lever is further provided with a plurality of openings 47 in any one of which a counterweight 48 may be suspended and to the end of the lever I attach one end of a chain 49 which passes over guide pulleys 50 to the coupling head 13 to which it is attached. Upon that end of the base plate 41 remote from the post 42, I secure a second post 51 and in the upper end of said post I mount an adjustable screw 52 which is disposed in the vertical plane of the lever 43 and is adapted to be engaged by the said lever and, therefore, serve as a stop and rest for the lever so that the closing movement of the valve may be limited as desired. By this means, I am enabled to prevent complete seating of the valve disk 53 so that the flow of steam to the burner 110 will not be absolutely cut-off and a slight supply of steam to the burner will be maintained so that any possible dripping of fuel at the burner will be neutralized and explosion, consequently, avoided. This precautionary arrangement is employed in addition to the burner structure heretofore mentioned, the latter operating automatically according to the pressure of the fuel and steam, respectively, in the burner proper. 115 The valve disk 53 is provided with a depending rim 54 having openings 55 therethrough and said openings, as clearly shown in Fig. 2, are contracted toward their upper ends. Obviously, as the valve rises from its seat 125 the flow of steam through the openings will be gradually accelerated and will be likewise gradually diminished as the valve moves toward its seat so that pounding and other abnormal strains upon the parts due to abrupt 130

cutting off or setting up of the flow of steam are eliminated.

Within the fuel pipe 24, I provide a regulating valve 56 which is of the same construction as the valve 39 just described and has its stem equipped with a yoke 57 engaged with a lever 58 fulcrumed upon a post 59 rising from the valve casing. The stop post 51, however, employed in connection with the steam-regulating valve is omitted from the fuel-regulating valve. The lever 58 is equipped with a counterweight 60 and a chain 61 is attached thereto and extends therefrom over guide pulleys 61' to the coupling head 13 to which it is attached. It will thus be seen that the valves 39 and 56 are controlled through the damper and the damper regulator and are automatically adjusted to set up or cut-off the flow according to the position of the damper.

The pump 23 is illustrated conventionally only and may be of any preferred form. The main fuel supply pipe 62 leads into the pumping chamber of the pump and the discharge pipe from said chamber is a part of the oil line 24, a branch return 24' connecting the discharge with the supply pipe 62. Within the branch return is a safety valve 63 which will automatically open if the pressure in the oil line should be excessive so that injury to the pump will be avoided and the back pressure will be relieved through escape of the oil and return of the same to the inlet pipe 62. Steam for driving the pump is supplied through a branch 64 leading from the branch 18 and communicating with the pump through a pipe 65. The pipe 65 has interposed therein a regulating valve 66 which may be of a well-known balanced valve type and controlled by a conventional flexible diaphragm pressure regulator, indicated at 67. One side of this pressure regulator communicates with a water cushion 68 likewise of conventional design and having a connection through a pipe 68' with the pump so that the movements of the pressure regulating diaphragm will be cushioned and the diaphragm will be protected from the action of heat, acids, gases and other deteriorating influences. A by-pass pipe 69 is connected at its ends with the pipe 65 above and below the valve 66 and within the said by-pass pipe I provide a regulating valve 70 of the same construction as the valves 27 shown in detail in Fig. 3 and previously described. Cut-off valves 71 are provided in the by-pass pipe above and below the valve 70 and a cut-off valve 72 is interposed in the pipe 65 above the by-pass. The handle 73 of the valve 70 is equipped with a counterweight 74 and a chain 75 is also attached thereto, said chain passing over guide pulleys 76 to a second weight 77 which is larger than the weight 74 and is slidably mounted in retainers or guides 78 of any convenient form.

Upon the lever 58, which is arranged immediately below the said weight 77, I secure a bracket 79 carrying a roller 80 at its upper end adapted to bear against the lower end of the weight 77 as will be readily understood upon reference to Fig. 1.

The several counterweights are so adjusted that the damper 8 will open somewhat or slightly in advance of the valve 39 and said valve will open slightly in advance of the valve 56 while the valve 70 will open only when the maximum capacity of the pump is needed. The valves and the damper will obviously close in the reverse order so that as the draft through the furnace increases an increased flow of steam and fuel is permitted and the draft will not be cut down to a predetermined minimum until after the flow of fuel and of steam has been cut-off. When the maximum steam pressure has been reached and is present in the steam dome, the parts are in the positions shown in Fig. 1. Should the pressure, however, drop owing to continued use of the steam, the damper regulator will be actuated so that a downward pull upon the coupling head 13 will be exerted and the damper 8 will, consequently, be opened more or less, in opposition to the weight 10, it being understood that when the pressure of the steam again rises the regulator 15 is moved in the opposite direction and the counterweight 10 serves to return the damper to closed position, the chain 11 being thereby kept taut at all times.

When the coupling head 13 moves downwardly a pull is exerted through the chains 49 and 61, respectively, so that the valves 39 and 56 will be successively opened. As is obvious, the pull upon the chains will lift the levers 43 and 58 in opposition to the weights 48 and 60 and the upward movements of the levers will be transmitted through the respective yokes to the valve stems and an increased flow of steam and fuel, therefore, permitted. Normally, the valve 70 is fully closed and the steam to drive the pump is supplied thereto through the pipe 65. If the steam pressure, however, should drop rapidly so that it reaches a very low point, the movement of the levers 43 and 58 will be great enough to fully open the valves connected therewith and this extended movement of the lever 58 will bring the roller 80 against the lower end of the weight 77 and will lift the same so that the chain 75 will be slackened and the handle 73 permitted to swing downwardly under the influence of the weight 74 so that the valve 70 will be opened and the steam will be admitted through the by-pass to the pump, thereby cutting out the regulator 67 and flowing with its full force to the pump unimpeded by the restricting influence of said regulator. I thus effect a step up in the action of the pump so that an increased

blaze will be quickly created in the combustion chamber of the furnace and the steam soon restored to the desired pressure.

It will be readily understood from the foregoing description, taken in connection with the accompanying drawings, that I have provided a very efficient apparatus which is of simple construction and arrangement and by the use of which the flow of fuel and of the steam to atomize the same will be regulated automatically by the draft through the furnace and the steam pressure so that the pressure of the steam will be kept substantially uniform within reasonable limits automatically. The operation of the controlling valves will be gradual and in proportion to the fluctuations in the steam pressure and when a maximum flow of fuel is needed, it will be quickly set up through the accelerated action of the pump. By permitting a slight flow of steam to the burners at all times, I eliminate the danger of fuel drips at the burner tips, due to fuel remaining in the supply lines after the fuel line has been closed, and I thereby avoid the smoke which follows from lack of atomization, and at the same time I prevent excessive waste of steam due to the blowing of steam into the furnace when the fires are out. The valves 27 are set to meet the peak load fuel requirements and by reason of the elliptical form of the outlet openings therein present an area which effects concentration of the fuel without constriction and obviates constant attention notwithstanding fluctuations in the load. A uniform ratio between the steam fuel and draft is maintained while at the same time I provide for a quick step up in the fuel pressure when the same is needed. All the parts of my apparatus are accessible so that repairs are facilitated when they are needed and the number of parts or valves are minimized and complicated mechanisms are eliminated. The steam pressure is maintained with a minimum of attendance and the fuel supply is controlled automatically with high draft efficiency and combustion. Excessive blowing or popping of valves with a consequent loss of steam is overcome and an economy in the use of fuel is effected. Inasmuch as the increase or decrease in the flow of fuel and steam is effected gradually the wear upon the furnace and boiler equipment is minimized so that the cost of upkeep will be slight and the life of the plant is prolonged.

Having thus described the invention, what is claimed as new is:

1. In an apparatus for the purpose set

forth, the combination of a supply line, a valve interposed in said line, a base plate secured upon said valve, a post rising from said base plate at one side of the valve stem, a lever pivoted upon said post and operatively connected with the valve stem, a stop rising from the base plate below said lever and adapted to be engaged by it whereby to prevent complete closing of the valve, a damper, and operative connections between the damper and the lever whereby the valve will be controlled by the damper.

2. In an apparatus for the purpose set forth, the combination of a fuel supply line, a steam supply line, an automatic damper, regulating valves interposed in the fuel line and the steam line respectively, connections between the damper and said valves whereby the valves will be controlled by the damper, and means for preventing complete closing of the valve in the steam supply line.

3. In an apparatus for the purpose set forth, the combination of a fuel supply line, a regulating valve in said line, damper-controlled means for adjusting said valve, a pump for driving fuel through said supply line, a steam pipe connected with the pump for supplying steam thereto to operate the same, a fuel pressure regulator interposed in said pipe, a by-pass connected with said pipe at opposite sides of the said regulator, a controlling valve within said by-pass pipe, and means whereby said valve will be opened when the regulating valve in the supply pipe is fully opened.

4. In an apparatus for the purpose set forth, the combination of a fuel supply pipe, a regulating valve in said pipe, damper controlled means for setting said valve including a lever operatively connected with the stem of the valve, a pump for forcing fuel through said supply pipe, a steam supply pipe leading into the pump, a pressure regulator interposed in said steam supply pipe, a by-pass pipe connected with said steam supply pipe at opposite sides of the regulator, a normally closed valve in said by-pass pipe, a weighted handle member for said valve exterior to the casing thereof, a vertically slideable overbalancing weight, a flexible connection between said weight and said handle member, and means on the lever connected with the fuel supply pipe regulating valve to lift said overbalancing weight and permit opening of the valve in the by-pass pipe.

In testimony whereof I affix my signature.

ROBERT H. IRVING. [L. S.]
